(57) **CLAIM**

The ornamental design for a lap desk, as shown and described.

DESCRIPTION

FIG. 1 is a top side perspective view of a “lap desk” in a closed position;

FIG. 2 is a front and top view thereof with the top lid and hatch in an open position;

FIG. 3 is a side view thereof with the top lid in an open position;

FIG. 4 is a front view thereof with the top lid in a partially open position; and,

FIG. 5 is a bottom view thereof in a closed position.

The cross-hatched shading illustrated on the bottom of the lap desk in FIGS. 1–5 represents a type of surface material and is understood to be distributed uniformly over the surfaces on which it is only partially shown.

The broken lines are included for the purpose of illustrating the environment of the design only and form no part of the claimed design.
